PITMAN CONNECTION

William Schwemlein, Parkersburg, W. Va., assignor to The Parkersburg Rig & Reel Company, Parkersburg, W. Va., a corporation of West Virginia

Application October 24, 1936, Serial No. 107,496

3 Claims. (Cl. 287—93)

This invention relates to pitman connections, and more particularly to a self-aligning detachable pitman head for use in connection with the pumping and drilling rigs employed in connection with oil wells.

As is well known, standard and similar drilling and pumping rigs employ walking beams to which power is transmitted through a pitman connection, by means of a suitable crank or wrist pin. In actual practice, it is impossible to maintain accurate alignment between the operating parts of the apparatus referred to, the result being that in prior constructions damage and excessive wear are caused in the operation of the apparatus.

In later constructions, this difficulty has been largely overcome by providing a connection between the pitman and the walking beam which not only permits rocking motion of the upper end of the pitman on an axis parallel to the rocking axis of the walking beam, but also permits swinging movement of the pitman with respect to the walking beam on an axis at right angles to the first named axis, thus permitting the walking beam to assume inaccurate or distorted positions without transmitting undue strain to the pitman.

Moreover, it has been proposed to provide a pitman head construction which will permit the pitman to be readily detached from the wrist pin, as is frequently necessary in the operation of an apparatus of this character. Such readily detachable devices are successful for their intended purpose, but they do not provide all of the characteristics desirable in an apparatus of this character.

An important object of the present invention is to provide a novel pitman construction wherein the pitman head is readily detachable from the wrist pin structure without sacrificing any strength in the assembled elements.

A further object is to provide a novel type of self-aligning connection between the piston head and the wrist pin.

A further object is to provide a novel bearing assembly between the pitman head and the wrist pin which is particularly efficient in operation and which provides the necessary strength to permit the device to be operated over long periods of time with a minimum degree of wear.

Other objects and advantages of the invention will become apparent during the course of the following description.

In the drawing I have shown one embodiment of the invention. In this showing:

Figure 1 is a side elevation of the lower end of a pitman,

Figure 2 is a central vertical sectional view through the same, and,

Figure 3 is a detail perspective view of the pitman head.

Referring to the drawing, the numeral 10 designates a pitman head as a whole having a circular lower end 11 within which is an integral internal flange portion 12 having a tapered central 10 opening 13 for a purpose to be described. The top of the pitman head is provided with spaced parallel arms 14 forming a yoke receiving the lower end of the pitman proper, indicated by the numeral 15. The pitman proper may be secured within the arm 14 in any desired manner, as by riveting or welding, as will be understood. A bearing block 16 is provided with a peripheral face 17 tapered to correspond to the taper of the opening 13 and receivable therein. 20

The internal flange 12 is thickened to provide a laterally extending flange 18 through which bolts 19 extend. The inner face 20 of the peripheral portion of the bearing block 16 lies inwardly of the plane of the adjacent face of the 25 flange 18, when the bearing block 16 is in operative position as shown in Figure 2. One end of each bolt 19 is threaded into a head 21 which is then welded in position as at 22 to form in effect, an integral part of the bolt. Each head 21 has 30 an engaging face contacting with the face 20 radially inwardly of the bolts 19. The opposite side of each head 21 is provided with a longitudinally extending lug 23 engaging in an annular recess 24 surrounding the flange 18. The outer 35 end of each bolt 19 is provided with a nut 25. It will be apparent that when the nuts 25 are drawn up tight the heads 21 engage the bearing block face 20 to force the conical face 17 snugly into the opening 13, properly centered with respect 40 thereto. The recess 24 and flange 18 serve to anchor the associated heads 21 against rotation as well as to steady such heads against any possible distortion.

The bearing block 16 is provided in its longitudinally outer end with an axial recess 26 receiving an outer ball race 27, the longitudinally inner end of which engages a shoulder 28 formed in the bearing block 16. The inner face of the race 27 is spherical, as indicated at 29, and the longitudinally outer end of the race 27 is flush with the corresponding end face of the bearing block 16. 45

Roller or similar bearings 30 are arranged in the race 27 and run on an inner race 31. This 55

race surrounds the adjacent cylindrical end 32 of a wrist pin 33. The longitudinally inner extremity of the end 32 of the wrist pin terminates in a shoulder 34 against which the longitudinally inner end of the inner race 31 engages.

The wrist pin is provided with a tapered portion 35 receivable in the usual opening in a conventional crank arm, a nut 36 being provided for drawing the wrist pin tightly into engagement with the crank arm. The wrist pin is provided intermediate its ends with an enlarged portion 37, the longitudinally inner end of which is adapted to seat against the crank arm when the apparatus is assembled. The enlarged portion of the wrist pin is provided with a peripheral groove 38 receiving a deformable packing 39 operating in an opening 40 formed in the bearing block 16.

The longitudinally outer end of the wrist pin is reduced and threaded as at 41 for reception in a nut 42 which is split at one side and adapted to be clamped against the threads 41 by a screw 43. It will be noted that the nut 42 seats against the adjacent extremity of the wrist pin end 32 and extends radially outwardly therebeyond to engage the adjacent end of the bearing race 31 to positively maintain the latter in position. A cap 44 is arranged over the outer end of the wrist pin to protect the bearing elements against the destructive action of foreign material and the cap 44 is provided with a lubricant fitting 45. The cap 44 also is provided with a flange portion 46 secured as at 47 to the bearing block 16, the flange 46 extending radially inwardly beyond the opening 26 to engage the outer race 27 to positively maintain it in position.

The operation of the device is as follows:

It will be understood that the upper end of the pitman 15 is connected to the walking beam by means of the character referred to which will permit universal movement of the pitman with respect to the walking beam. Since any desired form of universal pitman connection may be employed, it is believed to be unnecessary to illustrate such connection. It also will be understood that the present invention is not only adapted to be used in connection with standard rigs, but also in connection with twin crank pumping units.

The pitman obviously transmits movement from the wrist pin to the walking beam in the usual manner to rock the latter about its supporting axis. The walking beam is adapted to assume inaccurate or distorted positions without transmitting strains to the upper or lower bearing elements of the pitman, the upper end of the pitman being movable with respect to the walking beam to compensate for irregularities in movement through the use of the universal connection referred to. The pitman is also adapted to twist or to alter its angular position with respect to the axis of the wrist pin 33 because of the use of the self-aligning bearing within the bearing block 16. The spherical surface 29 obviously permits changes in the relative positions of the pitman and wrist pin, and accordingly the wrist pin is relieved of all strains except the normal loads intended to be carried thereby.

The assembly of elements is quite important not only in providing the results referred to but also in providing the necessary degree of strength and rigidity, while at the same time permitting the pitman to be disconnected from the wrist pin assembly, as is frequently necessary. Three of the bolts 19 and associated elements are preferably employed, as shown in Figure 1, although

any desired number of these units may be employed. The heads 21 constitute lugs which are operative for forcing the tapered face 17 of the bearing block 16 into snug operative engagement with the tapered opening 13, whereby the pitman head and bearing block operate, in effect, as a unitary structure. Relative movement between these elements is effectively prevented by the structure referred to, and accordingly it will be apparent that the feature of providing for the detachment of the pitman head is provided without sacrificing strength and durability.

The inner and outer bearing races 27 and 31 are effectively secured in position by the cap 44 and nut 42, respectively, the latter elements, in operation, being rigid with the bearing block 16 and the wrist pin, respectively. The deformable packing ring 39 permits the wrist pin to alter its angular position with respect to the bearing block 16, while at the same time, such sealing ring prevents the entrance of foreign material into the bearings.

When it is desired to disconnect the pitman from the wrist pin assembly, it merely is necessary to loosen the nuts 25, turn the lugs 21 ninety degrees, and pull or tap outwardly upon the ring 11 of the pitman head, whereupon the universal mounting of the upper end of the pitman permits the pitman to be swung outwardly and thus completely detached from the wrist pin assembly. The parts may be assembled with equal facility by swinging the pitman head inwardly into engagement with the bearing block 16, returning the lugs 21 to their normal positions, and then tightening the nuts 25. The heads or lugs 21 engage the bearing block face 20, and the inwardly extending lugs 23 engage within the recess 24 to steady the heads 21 and to prevent rotation thereof while the nuts 25 are being tightened.

From the foregoing it will be apparent that the present construction provides a particularly efficient and rugged connection between a pitman and wrist pin, while providing the desirable characteristic of self-alignment. Moreover, the pitman is very readily disconnected from the wrist pin assembly, and is so effectively connected thereto in operation as to provide, in effect, a unitary construction with the bearing block 16.

It is to be understood that the form of the invention herewith shown and described is to be taken as a preferred example of the same and that various changes in the shape, size and arrangement of parts may be resorted to without departing from the spirit of the invention or the scope of the subjoined claims.

I claim:

1. In a pitman connection, a pitman head, a wrist pin normally arranged at right angles to said pitman head, said pitman head having a flange lying in a plane at right angles to the normal position of the axis of said wrist pin and provided with a conical opening coaxial therewith, a bearing block having a conical face fitting within said opening, circumferentially spaced fastening elements carried by said flange and including heads engaging said block and portions of said flange to maintain said conical face in rigid engagement with said opening, said flange having a laterally extending flange through which said fastening elements extend and provided with an undercut recess engaging portions of the respective heads, and bearing means arranged between said wrist pin and said block.

2. In a pitman connection, a pitman head

having a conical opening, a bearing block having its radially outermost surface formed as a conical face engageable in said opening and having a shoulder adjacent the larger end of such face at right angles to the axis thereof, a wrist pin normally coaxial with said opening and having one end arranged within said bearing block and its other end projecting therefrom, bearing means between the first named end of said wrist pin and said bearing block, said conical opening decreasing in diameter away from the second named end of said wrist pin, and a plurality of circumferentially spaced bolt elements arranged parallel to the axis of said opening and having head members engaging said pitman head and said shoulder to clamp the conical face of said block in said opening, the other ends of said bolt members having detachable nuts arranged radially outwardly of said conical opening.

0 3. In a pitman connection, a pitman head

having a tapered opening therein, a block having a tapered outer face corresponding in shape to and receivable in said opening, said block having a shoulder at right angles to the axis of and adjacent the larger end of said tapered face, a 5 wrist pin assembly carried by said block and comprising a wrist pin, a bearing device for supporting said wrist pin with respect to said block, and means carried by said block for securing said bearing device to said block, the outer face 10 of said block defining the radially outer limits of said block and having all portions thereof lying radially outwardly of said wrist pin assembly to permit its removal from said opening without disassembling said wrist pin assembly, and 15 clamping bolts carried by said pitman head parallel to the axis of said opening and each having portions overlying said shoulder to clamp the tapered face of said block in said opening.
